Primary Examiner — Amy C Wierenga*Assistant Examiner* — Angel R Marrero-Arce(74) *Attorney, Agent, or Firm* — Jose Cherson Weissbrot(57) **CLAIM**

The ornamental design for a media player for swimming, as shown and described.

DESCRIPTION

FIG. 1 is a front perspective view of a media player for swimming showing my new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines shown in the drawings depict portions of the media player for swimming that form no part of the claimed design.
